Filed Apr. 11, 1960, Ser. No. 60,143

Term of patent 14 years

(Cl. D29—1)

Fig.1.

Fig.2.

Fig.3.

Fig.4.

Fig.5.

FIG. 1 is a front elevational view of a Christmas tree ornament, showing my new design;

FIG. 2 is a side elevational view thereof, taken from the right of FIG. 1;

FIG. 3 is a rear elevational view thereof;

FIG. 4 is a top plan view thereof; and

FIG. 5 is a bottom plan view thereof.

The broken-line showing of a plurality of the ornaments is for illustrative purposes only, showing the ornaments as arranged in a continuous string.

I claim:

The ornamental design for a Christmas tree ornament, substantially as shown and described.
